UNITED STATES PATENT OFFICE.

WILLIAM N. TITUS, JR., OF WATERTOWN, MASSACHUSETTS.

SPRING COMPRESSING AND ASSEMBLING DEVICE.

1,026,837.

Specification of Letters Patent. Patented May 21, 1912.

Application filed May 15, 1911. Serial No. 627,845.

To all whom it may concern:

Be it known that I, WILLIAM N. TITUS, Jr., a citizen of the United States, and resident of Watertown, county of Middlesex, 5 and State of Massachusetts, have invented an Improvement in Spring Compressing and Assembling Devices, of which the following description, in connection with the accompanying drawings, is a specification, 10 like letters on the drawings representing like parts.

In assembling the valve parts of gasoline or like engines after these have been taken apart for cleaning or renewal of broken 15 parts, it is a matter of considerable difficulty to compress and hold in a state of compression the stiff spiral springs which control the valves, as is necessary for replacing the springs in operative relation to 20 the valves.

The purpose of the present invention is to provide a compact and conveniently operable device for quickly compressing a spring to the extent desired, and cooperative therewith, means for then holding the 25 spring compressed and permitting it to be reassembled with the valve, before the holding means is released.

To this end the invention consists of a 30 device composed of relatively slidable members carrying plates to compress the valve between them, with means for automatically holding such relatively slidable members in the position to which they are forced in 35 compressing the spring, and in conjunction therewith, clamping devices adapted to be engaged over the ends of the spring while thus held compressed to hold the same after the compressing elements are released.

40 The invention will be more fully understood from the following detailed description taken in connection with the accompanying drawings and will thereafter be pointed out in the appended claims.

45 Referring to the drawings: Figure 1 is a central vertical section through the spring compressing elements, a spring being shown compressed thereby. Fig. 2 is an elevation at right angles to Fig. 1 with the handle 50 part of one compressing element removed and showing the clamping devices engaged with the spring. Fig. 3 is an end view taken

in section on line 3-3 of Fig. 2. Fig. 4 is an end view of the releasing nut.

A rod or bar 1 is provided with screw 55 threads 2 at one end for engagement by a hand nut 3 for slidably adjusting on said bar a cross plate 4 adapted to press against one side of the spring. The bar 1 may be in any desired cross section, but is preferably angular so that the parts slidable thereon may be fitted thereto and held from turning movement. As shown, this bar is hexagonal, this being a form especially adapted for use with ordinary types of 60 valve constructions. The bar 1 has slidably fitted thereto a relatively heavy sleeve 5 formed at one end with a cross plate 6 cooperative with the plate 4 for compressing the spring. The sleeve 5 carries a pawl 7 70 pivoted thereto at 8 and having its inner end normally pressed inward by spring 9 to engage ratchet teeth 10, formed for a distance along one side of the bar 1, this pawl having a usual finger piece 11. The outer 75 end of the sleeve 5 is formed as a threaded nipple 12 and with this is engaged a tubular extension 13, having threaded in the other end thereof a nipple 14 on a knob handle 15. A pair of clamps 16 are provided to engage 80 the spring as compressed between the plates 4 and 6, these clamps having fixed beaks 17 at one end for engagement over one end of the spring and slidable beaks 18 adjustable to engage the other end of the spring as by 85 knurled nuts threaded on the clamps. The slidable beaks 18 are held from turning so as to align with the beaks 17 by a key way and pin connection 20.

In operation, the bar 1 having been 90 drawn out of the sleeve 5, a spring 21 shown as provided with a usual washer disk 22, which is to be assembled with the valve, is slipped over the bar to rest on the plate 4. The bar is then slid up into the sleeve 5 95 until the plate 6 engages the other end of the spring and by pressing forcibly against the knob 15 with the projecting end 2 of the bar against some suitable fixed abutment, the spring may be instantly compressed to the extent desired and is held so compressed by the pawl 7 snapping into engagement with a tooth 10. While the spring is thus compressed, the clamps 16 are 100

engaged with the sides thereof, as shown in Figs. 2 and 3, and the slidable beaks 18 adjusted up by the nuts 19 so that the spring is gripped thereby. The pressure of the spring is, of course, at this time withstood by the engagement of the pawl 7 with a tooth 10 so that this pawl could not readily be disengaged by pressing on the thumb piece 11. By now turning the releasing nut 3 a small amount in the proper direction, the pressure of the spring is transferred from the plates 4, 6 to the clamp 16 so that the pressure being taken off from the pawl 7, it can be easily disengaged from the ratchet tooth and the bar 1 may then be withdrawn from the sleeve 5, leaving the spring held by the clamps 16 at its sides only, and thus free to be assembled with the valve. This provision of an instantly operable spring compressor along with the secondary releasing means, illustrated herein as the releasing nut 3 in conjunction with the secondary or holding clamps 16 co-operative as set forth, is of much practical importance in the saving of time and facilitating valve assembling and replacing, for example, enabling automobile engines to be repaired on the road and reassembled without loss of time, while the outfit is compact, simple and inexpensive.

Having described my invention, what I claim as new and desire to secure by Letters Patent is:

1. A device of the kind described, comprising members mounted one in relation to the other for guided free sliding movement, one of said members having a handle adapted to impart thrusts in the axial line of the device and the other member being adapted to engage an abutment in a manner to resist thrusts along said axial line, and both of said members extending to opposite sides of the axis of the device sufficiently to permit a spring to be symmetrically disposed about said axis and be engaged when compressed by each of the members on opposite sides of the axis, and means for detachably holding said members interengaged at will to maintain a spring under compression.

2. A device of the kind described, comprising members mounted one in relation to the other for guided free sliding movement, one of said members having a handle adapted to impart thrusts in the axial line of the device and the other member being adapted to engage an abutment in a manner to resist thrusts along said axial line, and both of said members extending to opposite sides of the axis of the device sufficiently to permit a spring to be symmetrically disposed about said axis and be engaged when compressed by each of the members on opposite sides of the axis, said members being formed to engage the spring at opposite

sides and to leave intermediate opposite side portions free and unobstructed so that holding clamps may be applied thereto, and means for detachably holding said members interengaged at will to maintain a spring under compression.

3. A device of the kind described, comprising members mounted one in relation to the other for guided free sliding movement, one of said members having a handle adapted to impart thrusts in the axial line of the device and the other member being adapted to engage an abutment in a manner to resist thrusts along said axial line, and both of said members extending to opposite sides of the axis of the device sufficiently to permit a spring to be symmetrically disposed about said axis and be engaged when compressed by each of the members on opposite sides of the axis, said members being formed to engage the spring at opposite sides and to leave intermediate opposite side portions free and unobstructed so that holding clamps may be applied thereto, and means for detachably holding said members interengaged at will to maintain a spring under compression, said means consisting of ratchet teeth on one of said members and a pawl on the other of said members engageable with such ratchet teeth.

4. A device of the kind described, comprising members mounted one in relation to the other for guided free sliding movement, one of said members having a handle adapted to impart thrusts in the axial line of the device and the other member being adapted to engage an abutment in a manner to resist thrusts along said axial line, and both of said members extending to opposite sides of the axis of the device sufficiently to permit a spring to be symmetrically disposed about said axis and be engaged when compressed by each of the members on opposite sides of the axis, said members being formed to engage the spring at opposite sides and to leave intermediate opposite side portions free and unobstructed so that holding clamps may be applied thereto, and means for detachably holding said members interengaged at will to maintain a spring under compression, said means consisting of ratchet teeth on one of said members and a pawl on the other of said members engageable with such ratchet teeth, one of said members having a further provision for a lengthening adjustment of its operative portion relative to the other member without disturbing the interengaging hold between the members.

5. A device of the kind described, comprising relatively slidable members formed to clamp between them a spring to be compressed with the spring engaged so as to have like pressures exerted thereon at opposite sides and with opposite exposed por-

tions to receive holding clamps, a pawl and ratchet locking connection between said members to hold the same with the spring compressed as desired, and separate means for releasing said members to permit the pawl and ratchet locking means to be disengaged.

In testimony whereof, I have signed my name to this specification, in the presence of two subscribing witnesses.
